US00D614582S

(12) **United States Design Patent**
Ye et al.

(10) **Patent No.:** **US D614,582 S**
(45) **Date of Patent:** **** Apr. 27, 2010**

(54) **CONNECTOR CONTACT**

(75) Inventors: **Chao-Yong Ye**, Tu-Cheng (TW);
Kai-Hsiang Chang, Tu-Cheng (TW);
Kuo-Chin Lin, Tu-Cheng (TW)

(73) Assignee: **Cheng Uei Precision Industry Co., Ltd.**, Tu-Cheng, Taipei Hsien (TW)

(**) Term: **14 Years**

(21) Appl. No.: **29/344,783**

(22) Filed: **Oct. 5, 2009**

(51) LOC (9) Cl. **13-03**

(52) U.S. Cl. **D13/154**

(58) Field of Classification Search D13/118-120,
D13/133, 146, 147, 154, 184, 199; 439/607-610,
439/845, 849, 870, 877, 884, 885

See application file for complete search history.
